UNITED STATES PATENT OFFICE.

ALFRED LAWRENCE, OF STAMFORD, CONNECTICUT, ASSIGNOR TO THE YALE & TOWNE MANUFACTURING COMPANY, OF STAMFORD, CONNECTICUT.

LOCK.

Application filed August 22, 1923. Serial No. 658,803.

This invention relates to improvements in locks and more particularly to such as door locks employing stop-work or dead-locking means for the latch bolt.

5 Locks of this type are often used on doors for public entrances or as night latches and it sometimes becomes desirable to have the bolt held in its inactive position during the day time.

10 An object of my present invention is to provide means, without complicating the mechanism with additional parts, whereby the stop plunger in cooperation with a part on the knob spindle, (the outside roll-back 15 on the knob spindle, for example) shall be operable to prevent return rotation when the latch bolt shall have been retracted and hence cause the latch bolt to be retained in retracted position.

20 The accompanying drawing illustrates a lock mechanism in which my improvements are embodied.

In the drawing, I have shown my improvements in a mortise lock of the type disclosed in patent to Reinhold Schoell January 9, 1917, No. 1,212,117, but it will be understood that my improvements are applicable to any lock of this general type in which stop-work is employed.

30 In the lock structure shown in the drawing, the lever 1 is pivoted to the lock casing and is normally held by a spring 2, in position to be engaged by the cam 3 actuated by the knob spindle 4 and the outside roll-back which is indicated at 5. The lever 1 is provided with a laterally projecting pin 6 adapted to engage the dead-locking lever 7 at the rear of its pivot 8, so that when the lever 1 is moved by either the key or knob 35 mechanism, the pin 6 engaging the lever 7 will elevate the rear end and depress the front end of said lever and remove the front end from the path of travel of the bolt and permit the latter to be retracted.

40 The lever 1 rests in front of the cross-bar 9 at the rear end of the tail 10 of the bolt 11, hence when moved rearwardly either by the key or knob mechanism it will retract the bolt, which is normally projected by the 45 spring 12.

As is common in locks of the type to

which my improvement relates, stop-work is provided to prevent operation of the latch bolt by manipulation of the knob or to permit such operation. This stop-work includes a manually operable stop-plunger 13 which is cooperable with the roll-back 5. When this plunger is moved out of operative relation to the roll-back, the mechanism may be operated by turning the knob spindle 4 55 to retract the bolt. The roll-back 5 is notched at its center and also near one end, providing a shoulder 14. When the bolt is projected, if the stop-plunger be moved inwardly it will engage the central notch of 60 the roll-back, as shown in the drawing, and the knob-spindle will then be held against movement to retract the bolt and the bolt can be retracted only by manipulation of the key-controlled means. If the plunger 13 be 65 shifted outwardly, the knob spindle will be free to turn, and if it be turned to retract the bolt, the shoulder 14 of the roll-back will be disposed in the path of movement of the inner end portion of the stop-plunger 13. 70 By now pressing the stop-plunger 13 inwardly, the inner end portion thereof will become engaged with the shoulder 14 of the roll-back 5, preventing return movement of the latter and thus retaining the latch bolt 75 in its retracted position, inasmuch as the lever 1 bearing against the cross-bar 19 will be held in the retracted position by the roll-back and the co-acting cam 3.

Having fully described my invention what 80 I claim as new and desire to secure by Letters-Patent, is:

In a lock, the combination of a bolt, a lever pivoted below the bolt and engaged therewith to retract the same, a knob spindle, 90 a roll-back carried by the spindle and operable to rock the lever and effect retraction of the bolt, the roll-back being provided in its edge with a central notch and with a stop plunger slidable to and from the roll-back to engage the notch and prevent rocking of the spindle or to engage the shoulder and hold the bolt retracted.

In testimony whereof, I have signed this 100 specification.

ALFRED LAWRENCE.
